Atty's

UNITED STATES PATENT OFFICE.

WILLIAM S. HUNKINS, OF LOS ANGELES, CALIFORNIA.

HOSE-SUPPORTER.

1,398,487.

Specification of Letters Patent. Patented Nov. 29, 1921.

Application filed December 14, 1920. Serial No. 430,622.

To all whom it may concern:

Be it known that I, WILLIAM S. HUNKINS, a citizen of the United States of America, residing at Los Angeles, California, have invented a new and useful Hose-Supporter, of which the following is a specification.

My invention relates particularly to devices of the character set forth in my Patent No. 1,354,485, of October 5, 1920. In my former patent I have shown and described a number of different forms of bushings, and broadly and specifically claimed certain combinations. My present invention applies to a construction of the bushings and a method 15 of securing them to the tape.

The main object is to provide a simple and inexpensive form of construction, such that the tape may be readily secured to the bushing by anyone, and such that any form of 20 tape may be used.

Figure 1 is a front view of a construction embodying my invention;

Fig. 2 is an edge view of the bushing and showing the method of attaching the tape; 25 Fig. 3 is a plan view of the bushing and its attached parts;

Fig. 4 is a side view of the same;

Fig. 5 is a vertical sectional view of a slightly modified form;

30 Fig. 6 is a front view of a modified form of bushing with the tape attached;

Fig. 7 is a transverse sectional view of the bushing;

Figs. 8 and 9 are side and sectional views, 35 respectively, of another form of bushing;

Figs. 10 and 11 are side and end views, respectively, of another form of bushing attached to a tape; and

Fig. 12 is a plan view of the bushing showing 40 tangs for fastening it to the tape.

14 indicates a fragment of a waist, corset or other garment from which the hose supporter 15 is adapted to be suspended. 16 indicates the tape, which is usually non- 45 elastic and stitched or otherwise suitably secured to the garment. 17 is a fastening device having a pin or bar portion 18 adapted to be inserted into the bushing 19. The fastening device 17 is secured to the upper 50 end of the hose supporter 15 and the bushing is secured to the lower end of the tape 16.

The bushing is formed by rolling or curling a piece of metal into the desired shape. In the form shown in Figs. 1 to 4 inclusive,

the bushing has a plate 20 with cross bars 21 and 22 and slots or passages 23 and 24 for the tape. By offsetting the bars 21 and 22, as shown in Figs. 2 and 3, assembly of the tape is facilitated.

In the form shown in Fig. 5 the cross bar 60 22' is shown in the same plane as the plate 20, while the bar 21 is offset, as in Figs. 2 and 3. The offsetting, however, in all three of these figures, is exaggerated over what it would ordinarily be in practice.

65 The bushing 25 of Figs. 6 and 7 is formed with depending edges 26, which are slotted at 27 to receive the tape 28. This form of device is somewhat more compact than the form shown in Figs. 1 to 5. I have also 70 shown the bushing as somewhat oval in cross section, with its minor axis vertical, so that it is better calculated to withstand the strains applied to it, both laterally and vertically. The lateral strains, being, of course, 75 external, tend to close up the tube laterally, whereas the vertical strain is internal and tends to deform the tube in substantially the same manner by elongating its minor axis.

In the form shown in Figs. 8 and 9 the 80 bushing 29 has a single bar 30 with a slot 31 between the bar and the bushing. This requires even less metal than the other form.

In the form shown in Figs. 10, 11 and 12 the bushing 32 is provided with tangs 33, 85 which are adapted to be bent around the opposite edges of the tape 34.

All of the forms shown herein are adapted to be assembled by hand by anyone. It will be obvious, however, that in the form shown 90 in Figs. 10, 11 and 12 the tangs 33 may be bent inward hard enough to actually bite into the fabric of the tape, so that it will ordinarily be impossible to separate them without the use of tools. Such connection 95 will obviously best be effected by the use of some form of tool.

I claim:

1. In a hose supporter, a bushing, a tape 100 embracing said bushing, and members connected to the ends of said bushing and embracing one fold of said tape, including the outer surface thereof.

2. In a hose supporter, a bushing constituting a pin tube, a tape embracing said bushing, and a cross bar connected to the opposite ends of said bushing only and providing a slot between the wall of said bush-

ing and said bar for only one thickness of said tape.

3. In a hose supporter, a bushing constituting a pin tube, a bar connected to only the opposite ends thereof and forming a slot between the wall of said bushing and said bar of a size sufficient to receive only one thickness of tape, and a tape embracing said

bushing and having one fold thereof extending through said slot.

4. In a hose supporter, a bushing, and a tape embracing said bushing, said bushing being oval in cross section and having its major axis transverse to the plane of said tape.

WILLIAM S. HUNKINS.
